UNITED STATES PATENT OFFICE.

JOHN E. WARREN, JR., OF NEWARK, NEW JERSEY, ASSIGNOR TO HERMAN TAPPAN, OF NEW YORK, N. Y.

DESIGN FOR A PERFUMERY-HOLDER.

SPECIFICATION forming part of Design No. 21,973, dated November 8, 1892.

Application filed September 24, 1892. Serial No. 446,839. Term of patent 3½ years.

To all whom it may concern:

Be it known that I, JOHN E. WARREN, Jr., of Newark, in the county of Essex and State of New Jersey, have invented and produced
5 a new and original Design for a Perfumery-Holder, of which the following is a full, clear, and exact description.

Reference is to be had to the accompanying drawing, forming a part of this specification,
10 in which the figure is a perspective view showing my design.

The essential feature of my design consists in the representation of a post A, ornamented at its lower end by a base and at its upper end by a bottle-like figure B.
